US0D1084474S

(12) **United States Design Patent** (10) Patent No.: **US D1,084,474 S**
(45) Date of Patent: ** Jul. 15, 2025

(54) **LIGHTING FIXTURE**

(71) Applicant: **SIGNIFY HOLDING B.V.**, Eindhoven (NL)

(72) Inventors: **Yong Jun Yj Hwang**, Shanghai (CN); **Yang Chen**, Shanghai (CN); **Keijing Wang**, Shanghai (CN)

(73) Assignee: **SIGNIFY HOLDING B.V.**, Eindhoven (NL)

(**) Term: **15 Years**

(21) Appl. No.: **29/904,254**

(22) Filed: **Oct. 3, 2023**

(51) LOC (15) Cl. **26-05**

(52) U.S. Cl.

USPC **D26/107**; D26/93

(58) **Field of Classification Search**

USPC D26/61, 62, 63, 93, 104, 105, 106, 107, D26/108, 110, 112, 128

(57) **CLAIM**

The ornamental design for a lighting fixture, as shown and described.

DESCRIPTION

FIG. 1 is a perspective view showing my design;
FIG. 2 is another perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof; and,
FIG. 8 is a bottom plan view thereof.
